UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

BUTTON CLAMP.

Application filed December 11, 1924. Serial No. 755,175.

In the manufacture of garments, or the like, there are often occasions when buttons widely differing from each other in size are to be sewed to the same piece of goods. As heretofore constructed, however, the clamps for holding the buttons in position for machine sewing have been incapable of accommodating buttons of greatly differing sizes so that it has been necessary when sewing on buttons of greatly different sizes to change from one clamp to another or to limit the operations of one machine to buttons within a certain range of sizes and to employ one or more additional machines having clamps capable of handling buttons of the other sizes. In either case two or more handlings of each garment or other piece of goods are necessary to sew on all the buttons required and such handling represents a considerable time factor in the expense for labor. Of course where it is necessary to change the clamps on a single machine this adds another important time factor to the labor cost.

An important purpose of the present invention, therefore, is to provide a construction of clamp capable of properly handling buttons having such a great range in sizes that changes of clamps or different machines for the same goods are rendered unnecessary. The clamp of the present invention is capable of properly handling buttons of sizes from ten to one hundred and twenty lines or more, there being forty lines to an inch of diameter. So far as I am aware no button clamp has heretofore been devised capable of handling buttons having size variations of more than sixty lines.

This invention also provides an adjustment mechanism by which opening and closing movement of these jaws to any extent desired may be rapidly and easily effected.

A further feature of the invention relates to the construction whereby a spring-pressed plunger for depressing the clamp is also employed to hold the clamp in proper lateral position.

For a more complete understanding of this invention, reference may be had to the accompanying drawings in which

Figure 1 is a fragmentary side elevation of a button sewing machine showing the clamp of the present invention in position thereon.

Figure 2 is a fragmentary plan of the

button-clamping mechanism showing the position of the jaws for engaging a button of large diameter.

Figure 3 is a similar view showing the jaws engaging a button of small diameter.

Figure 4 is a plan view of the clamp.

Figure 5 is a front elevation thereof showing a button of large size held thereby.

Figure 6 is an inverted plan of the clamp.

Referring first to Figure 1, at 1 is indicated the machine head having the usual sewing arm 2 extending upwardly therefrom and then substantially horizontally thereover where it carries a head 3 in which is mounted the needle bar 4 carrying the needle 5 and certain other sewing instrumentalities in the usual manner. The needle 5 in its sewing strokes passes down through the cloth plate 6 on a work table 7 into cooperative relation with the looper 8. The button clamp 10 is carried by an angle piece 11 which is pivoted as at 12 to a portion of the machine closely adjacent to the rear end of the arm 2, either to the machine frame or to a member movable relative thereto, so that the clamp 10 may be lifted to raise the button from the cloth plate, the pivot 12 being as far removed from the button-engaging portion of the clamp as is convenient.

The clamp itself comprises a support 20 which is fixed to the arm 11 as by means of bolts 21, this support carrying a pair of opposed button clamping jaws 22 and a third jaw 23. The jaws 22 as shown extend substantially the length of the support 20 and at their rear ends are fulcrumed on the pivot screws 25 which are back as far as possible toward the pivot 12. By extending the jaws rearwardly in this manner their forward button-engaging portions 30 move in arcs of a large diameter circle as shown by the dotted lines *a*—*b* in Figures 2 and 3. It is found in actual practice that if the fulcrum of the jaws is positioned $6\frac{1}{8}$ inches from the button-engaging portion the clamp will satisfactorily take buttons of diameters coming within the range of ten to one hundred and twenty lines. At the forward end of the support 10 the jaws 22 are supported close to its lower face throughout their extent of pivotal motion by means of a transverse bar 35 on which these jaws ride, this bar being fixed to the support as by means of a screw 36. This bar and support act to prevent substantial motion of the jaws later-

ally of their directions of pivotal movement. Forwardly of this bar the jaws are downwardly turned as at 40 and then are bent forwardly terminating in the button-engaging portions 30. As shown these button-engaging portions have flanges 45 at their upper edges projecting toward each other and also are provided with resilient fingers 46 projecting inwardly at the lower face of the jaws, these fingers being movable toward and from the flanges 45, being guided by pins 47 passing through perforations 48 in the jaws. The extent of downward motion of these fingers relative to the jaws is limited by inturned ears 49 projecting over the upper faces of the jaws, this construction being for the purpose of permitting the jaws to accommodate themselves to buttons of different thicknesses but yet insuring a positive upward movement of the fingers 46 to raise the button from the work at the end of the sewing operation. This construction is fully described and claimed in my application for patent, Serial No. 729,881, filed August 4, 1924, for button clamps.

The third jaw 23 is fixed to the forward end of a plate 50 slideable on the lower face of the support 20 being held thereto by means of screws 51 having their heads 52 riding on the upper face of the support and shank portions 53 extending through a slot 54 in the support and engaged in the plate 50. In order to adjust the freedom of sliding motion of this plate, screws 55 are passed therethrough engaging in threaded openings in the shanks 53 of the screws 52, the heads of these screws 55 bearing against the lower face of the plate 50. The plate 50 is provided with a pair of inclined slots 60 within which ride guide screws 61 threaded into the jaws 22 by which screws sliding of the plate 50 causes the jaws 22 to approach and recede from each other swinging about their pivot screws 25. The parts are so proportioned that the central jaw 23 moves back and forth toward the transverse lines of motion of the button-engaging portions of the side jaws 22 so that at all times it is in position to engage the rear edge of a button of sufficient diameter to fit between the side jaws in such a manner that the center of a button engaged by the jaws is always in the same place regardless of the size of the button.

The position of the jaws for engaging a button of a large diameter is shown in Figure 2, it being noted that the side clamping jaws engage the button slightly forwardly of a lateral diameter thereof, such as diameter being indicated by the lines *c-d* in Figure 2, while the middle jaw 23 engages the rear edge of the button midway between the side jaws. By engaging the button in this manner it is so securely held in position that if a forward and rearward motion of the button is to be affected by movement of the

clamp, as, for example, when four hole buttons are to be sewed, the button is not pulled out from between the clamping jaws.

Similarly when a small button is engaged as shown in Figure 3 the side clamping jaws 70 engage the button in such a manner that rearward motion of the clamp will not act to pull the button from the clamp and the rear jaw 23 is in position to support the rear edge of the button. In every case the 75 center of the button is held in the same position regardless of its size. In order that the jaws may be held at any desired limit of inward motion to conform to any size button desired and yet permit the jaws to 80 be yieldingly pushed apart slightly to permit the insertion or removal of a button, a quick adjusting stop device is provided together with spring means for normally holding the jaws as close together as is permitted 85 by such stop device. The stop device comprises an abutment block 65 fixed to one of the jaws 22 slightly forwardly of its pivot screw 25, which abutment is adapted to be contacted by the inner end of a screw 66 90 threaded through the opposite jaw 22. This screw 66 is provided with a knurled head 67 by which it may be turned and it may also have threaded thereon a lock nut 68 between which and the adjacent jaw 22 a split spring 95 washer 69 may be placed.

As the stop device is positioned close to the fulcrums of the jaws 22, it is evident that a small adjusting motion thereto will impart a considerable motion to the button-engaging portions of the jaws. The spring for resiliently holding the jaws to their inner limit of motion as shown comprises a substantially U-shaped spring wire 70 having its ends inwardly turned as at 71 and engaging in depressions 72 in the outer edge of each of the jaws 22. The mid portion of this spring wire passes to the rear of the pivot screws 25 and is preferably supported in the plane of the jaws 22, for this purpose a plate 75 being shown as fixed to the lower face of the support 20 by means of a screw 76, this plate having its rear end extending under the spring wire 70. In order that the jaws may be opened against the tension of this spring to permit the ready insertion of the button the plate 50 is shown as provided with a pair of forwardly and downwardly extending finger pieces 80, either of which may be pressed upon by the operator to push the 120 slide 50 rearwardly, thus to retract the central button-engaging jaw 23 and open the jaws 22.

For the purpose of raising the button clamp about the pivot 12 a chain 85 is shown 125 as fixed to the upper face thereof on a screw 86, this chain extending to the usual rock shaft (not shown) in the head of the machine which is commonly treadle actuated to raise the clamp. The clamp is normally 130

pressed down against the work by means of a spring-pressed plunger member 87 which, as shown in Figure 5, is provided at its lower end with a foot 88 which rides in a groove 89 in a bridge piece 90 cut away at its under face as at 91 to permit the head 52 of one of the screws 51 to pass thereunder, this bridge piece being fixed to the upper face of the support 20 as by means of screws 92. By this inter-engagement between the lower end of the spring plunger, which is unattached to the clamp, and the bridge piece a lateral support to the clamp in its raising and lowering movements is afforded. The spring plunger shown may be of the general construction more fully illustrated in my Patent No. 1,583,062, granted May 4, 1926.

Having thus described an embodiment of this invention, it should be evident to those skilled in the art that various changes and modifications might be made therein without departing from its spirit or scope as defined by the appended claims.

25 I claim:

1. In combination with a button sewing machine having a frame, a sewing arm overhanging said frame, sewing instrumentalities carried at the free end of said arm, a member pivotally supported adjacent to the rear end of said arm, and a button clamp carried by said member, said button clamp comprising a pair of opposed button-clamping jaws pivotally mounted adjacent to the pivotal mounting of said member and having button-engaging faces positioned to hold a button in operative relation to said instrumentalities.

2. In combination with a button sewing machine having a frame, a sewing arm overhanging said frame, sewing instrumentalities carried at the free end of said arm, a member pivotally supported adjacent to the rear end of said arm, and a button clamp carried by said member, said button clamp comprising a pair of opposed button-clamping jaws pivotally mounted adjacent to the pivotal mounting of said member and having button-engaging faces positioned to hold a button in operative relation to said instrumentalities, said button-clamping jaws being movable on said pivots to conform to buttons of widely different diameters.

3. A button clamp having opposed button-engaging jaws, and means for pivotally supporting said jaws remote from their button-engaging portions whereby said button-engaging portions move toward and from each other for such substantial distances along approximately straight paths as to properly engage buttons differing in size by more than sixty lines.

4. A button clamp comprising a support, means for pivotally mounting said support, the pivot being adjacent to the rear end of

said support, a pair of button-clamping jaws each pivoted at the rear end of said support and extending forwardly thereof, said jaws having opposed button-engaging faces at their forward ends and means for effecting simultaneous and equal movements of said jaws toward and from each other to hold buttons of diameters differing from each other by more than sixty lines with their centers in the same position.

5. A button clamp comprising a support, means for pivotally mounting said support, the pivot being adjacent to the rear end of said support, a pair of button-clamping jaws each pivoted at the rear end of said support and extending forwardly thereof, said jaws having opposed button-engaging faces at their forward ends, a member movable forwardly and rearwardly on said support and having connection to said jaws whereby movement of said member causes simultaneous and equal movements of said jaws toward and from each other to hold buttons of sizes differing by more than sixty lines with their centers in the same position, and means for moving said member.

6. A button clamp comprising a pair of button-engaging jaws, and means for pivotally supporting said jaws at such a substantial distance from their button-engaging portions that such button-engaging portions move along approximately straight lines from and within the limits of sizes of ten line and one hundred and twenty line buttons placed therebetween.

7. A button clamp comprising a support, a pair of button-engaging jaws each pivoted adjacent to the rear end of said support, a spring for pressing the button-engaging portions of said jaws together, and a screw carried by one of said jaws adjacent to its pivot and operatively engaging the other of said jaws adjacent to its pivot for adjustably limiting the extent to which said button-engaging portions shall approach each other.

8. In a button sewing machine, a button clamp, means for mounting said button clamp whereby it may be raised and lowered relative to said machine, and a spring-pressed plunger engaging said clamp and yieldingly holding it in lowered position, said clamp having a longitudinal guideway therein within which the lower end of said plunger rides to prevent relative lateral motion between said clamp and plunger.

9. In a button sewing machine, a button clamp, means for mounting said clamp whereby it may be raised and lowered relative to said machine, and a spring pressed plunger unattached to but engaging said clamp and yieldingly holding it in position, said plunger and clamp being formed complementally to prevent relative lateral motion therebetween.

115

120

125

130

10. A button clamp comprising a support, a pair of button clamping jaws pivoted to said support back of its forward portion, connections between said jaws insuring simultaneous motion thereof, and means independent of said connections acting at the forward portion of said support for maintaining said jaws in proper positions relative to said support.
11. A button clamp comprising a support, a pair of button clamping jaws pivoted to said support back of its forward portion, and means fixed at the forward portion of said support for maintaining said jaws close to said support.
12. A button clamp comprising a support, a pair of button clamping jaws pivoted to said support back of its forward portion, and a bar fixed in spaced relation to said support at its forward portion, said jaws riding in said space.
13. A button clamp comprising a support, a pair of button clamping jaws pivoted to said support, a third jaw slidably carried by said support between said pivoted jaws, a cam plate carried by said sliding jaw and engageable with said pivoted jaws to effect simultaneous movement of all of said jaws in both opening and closing, and means independent of said sliding jaw and acting on said pivoted jaws at the forward end of said support for holding said pivoted jaws to said support.
14. A button clamp comprising a support, a pair of button clamping jaws pivoted at their rear ends to said support, connections between said jaws insuring simultaneous motion thereof, and means independent of said connections acting on said jaws at their forward portions throughout their extent of pivotal motion to prevent them from substantial movement in directions laterally of such pivotal movement relative to said support.

In testimony whereof I have affixed my signature.

ROBERT L. LYONS.
